RAILWAY SIGNALING SYSTEM

Wade H. Reichard, Rochester, N. Y., assignor to
General Railway Signal Company, Rochester,
N. Y.

Application December 28, 1935, Serial No. 56,488

12 Claims. (Cl. 246—38)

This invention relates in general to railway signaling systems, and more particularly to the trackway portion of a combination wayside and cab signaling system for railroads.

It is generally proposed in accordance with the present invention to provide an organization of wayside circuits and apparatus in a railway signaling system whereby wayside signals having at least three distinctive indications are controlled and whereby these signals are energized only when approached by a train, all without the use of control line circuits. It is further proposed to include in such a wayside signaling system means for applying cab signal controlling energy to the track in accordance with forward traffic conditions whereby to provide a combination of wayside and cab signals employing a minimum of trackway apparatus and circuits.

Other objects, purposes and characteristic features of the present invention will be apparent as the description thereof progresses, during which references will be made to the accompanying drawing which illustrates in a diagrammatic and conventional manner one specific form of the present invention.

A portion of a railway system has been illustrated in the accompanying drawing as divided by insulating joints J into track sections or blocks 1, 2 and 3, and inasmuch as the apparatus is the same for each block, the same reference character will be used to designate like pieces of apparatus at the different blocks with an exponent corresponding to the particular block with which it is associated. The block 3 has been shown as occupied by a train represented by a single pair of wheels and axle 5, which train carries the usual cab signaling equipment which is illustrated diagrammatically as receiving inductors 6 and 7, one carried over each rail, which inductors are inductively energized by alternating current impulses flowing in the rails and this energization is amplified by the usual amplifier A to energize the relay MR. The relay MR when effectively energized closes front contact 8 to light a clear signal lamp TC and when the alternating current impulses are not flowing in the track rails, the relay MR is deenergized to close back contact 8 and light the restrictive signal lamp TD, all in a manner obvious from the drawing.

Wayside signals of any suitable type are located at the entrance of each block, which signals have been illustrated as the color light type having a green clear light G, a yellow caution light Y, and a red danger light R. These wayside signals are controlled in accordance with the character of

energization of the associated track circuit which is reflected by the condition of two home control relays HF and HB and a distant control relay D, and these signals are normally deenergized except when an approaching train drops an approach lighting relay V controlled by the rear adjacent track circuit as will be later described.

The apparatus for selecting the character of the track circuit energization at the exit end of each block comprises an interrupter or coder C of the usual type having a motor (not shown) of a constant speed type arranged to operate contacts designated as C180 and C175 at different rates, or for example, it will be considered that contact C180 is operated at a rate of 180 times per minute and contact C175 at 75 times per minute. A code repeating relay CP is provided to repeat the operation of either contact C180 or C175 according to the condition of the home relays HF and HB as will be later described. A battery B is connected across the exit end of each section through a front contact of the code repeating relay CP, which battery B supplies direct current energy flowing through the rails of the associated track section in series to operate a code following track relay CT connected across the rails at the entrance end of each section. In this manner, the usual direct current coded track circuits are provided in which the code following track relays CT are normally operated in synchronism with the associated code repeating relay CP which is in turn operated at either of two rates by the associated coder C.

The impulses of alternating current which are received by the car carried inductors 6 and 7 must of course be applied at the exit end of the track sections, and in the present system this alternating current energy is derived from a transmission line 10 extending along the trackway and energized from a generator GE which provides a distinctive frequency such as 100 cycles per second. The primary of a transformer TA at the exit end of each section is selectively connected across this transmission line 10 according to the condition of the home relays HF and HB associated with the forward adjacent track section, and the secondary of this transformer TA is connected across the rails through a back contact of the associated code repeating relay CP.

In the illustrated condition of the present system, the rails of section 3 are shunted by a train represented by the wheels and axle 5 so that the track relay CT³ is deenergized continually which deenergizes both the home relays HF³ and HB³ as will be obvious from the following descrip-

tion of the control of HF and HB relays. The code repeating relays CP² is operated over a circuit from the (+) terminal of a suitable source of direct current energy, through coder contact C15, back contact 12 of relay HF³, through the windings of CP², to (-), whereby the armature of relay CP² is operated at the rate of 75 times per minute.

The battery B² is thereby intermittently connected across the rails of section 2 through the usual series resistor S² and the windings of the A. C. relay V², but these V relays are of the alternating current induction type so that this direct current does not affect the operation of their armatures. These current impulses of the 75 code rate however flow through the track rails in series to cause the armature of the code repeating track relay CT² to operate at the rate of 75 times per minute. When the code following track relay CT² is energized, the home relay HF² is picked up through front contact 13, and when deenergized the home relay HB² is picked up through back contact 13 and front contact 14 of relay HF², and as indicated on the drawing, these home relays HF and HB are of the slow releasing type whereby their armatures are retained in their attracted position during the intermittent periods of deenergization of their windings.

A decoding transformer TC is provided at each block with different portions of the primary alternately energized with direct current by a contact of the associated code following track relay CT to provide an alternating current secondary voltage of a frequency corresponding to the rate of operation of the associated code following track relay. This alternating current voltage of the secondary of transformer TC flows through a tuning circuit represented by a condenser M and a tapped inductance L so arranged as to pass an amount of current to a full wave rectifier K which is effective to pick up the associated D relay only when the frequency of the secondary voltage of the transformer TC corresponds to the 180 code rate of operation of the track relay CT.

Inasmuch as the track relay CT² in block 2 is operated at the 75 code rate as previously described, the energization of transformer TC² changes at the rate of 75 times per minute, this energization being from (+), through front contact 16 of relay CT², through one half of the primary of transformer TC² to (-) through a center tap, which circuit is shifted by the closing of back contact 16 to the other half of the primary winding. This alternate primary energization produces an alternating flux to induce an alternating current in the secondary of transformer TC² of 75 cycles per minute. This frequency is tuned out by the selected values of condenser M² and inductor L² so that the voltage impressed on the full wave rectifier K² by a tapped portion of inductor L² is not sufficient to attract the armature of relay D². It will be clear however, that if the armature of relay CT² were operated at the 180 code rate, this tuning arrangement would be in resonance to provide an output sufficient to attract the armature of relay D², and such a condition would exist at all unoccupied blocks in the rear of block 2.

In order to provide normally deenergized wayside signals, alternating current energy is superimposed on the track circuits at the entrance end of each section, or a transformer TB is provided with its primary energized from a suitable source of alternating current such as from the power line 75 10 and with its secondary connected across the

rails at the entrance end of the associated section in series with the usual series impedance RS. The current from the secondary of transformer TB flows through the rails in series to energize the associated alternating current relay V when a front contact of the associated code repeating relay CP is closed, and through the associated track battery B. When the associated track section is unoccupied, the V relay is intermittently energized due to the oscillation of the associated code repeating relay CP, and these V relays are sufficiently slow releasing that their armatures remain in their energized position during such intermittent energization.

When, with the apparatus of the present system in its illustrated condition, a train enters section 1, it will be clear that the alternating current energy applied at the entrance end of section 1 by a transformer TB (not shown) will be shunted away from relay V¹ thus causing its armature to be released, whereupon the yellow signal lamp Y² will be energized from (+), front contact 18 of relay HB², front contact 19 of relay HF², back contact 20 of relay D², through the yellow light Y² and through back contact 21 of relay V¹, to (-). Likewise it will be clear that the primary of transformer TA¹ is connected across the line wires 10 through front contacts 24 and 25 of relays HB² and HF² respectively, so that alternating current from the secondary of transformer TA¹ is applied to the exit end of section 1 through back contact 27 of relay CP¹. Alternating current impulses are thereby applied to the exit end of the track circuit of section 1 of the 180 code rate due to the operation of the code repeating relay CP¹ by the contact C180 of coder C¹ through front contacts 29 and 30 of relays HB² and HF² respectively. The receiving coils of the present train traversing section 1 are inductively energized by the alternating current impulses to energize the car carried control relay and light the clear cab signal lamp, thereby indicating on the train that sections 1 and 2 are unoccupied.

When the present train approaches section 2, the energization of the yellow signal lamp Y² indicates that section 2 is unoccupied but that section 3 may be entered only at minimum speed, and inasmuch as relays HF³ and HB³ are both deenergized, there are no impulses of alternating current applied to the exit end of section 2 due to open front contacts 32 and 33, and consequently a restrictive cab signal indication will be displayed when this train enters section 2. However, if the forward train illustrated as occupying section 3 progresses out of section 3 during the time that the rear train now under consideration is traversing section 2, it will be clear that the home relays HB³ and HF³ will pick up to energize the primary of transformer TA³ through front contacts 32 and 33 thereby supplying alternating current impulses to the exit end of section 2. In this manner the restrictive cab signal indication on the rear train will be changed to a clear indication to inform the engineer that section 3 has become less restrictive thereby allowing the speed of the rear train to be accordingly increased.

In this manner a signal system has been provided wherein coded track circuits are employed to provide the distant control of wayside signals according to the rate of direct current track circuit impulses to thereby avoid the use of control line wires, and these direct current impulses are separated by impulses of alternating current to 75

provide the track circuit energy used to condition car carried cab signals or train control apparatus. The track circuits of the present system have been further utilized to provide the approach lighting of the wayside signals also to avoid the use of control line wires, by means of a source of alternating current energy superimposed on the direct current coded track circuit to control an alternating current relay at the exit end of each section. This relay is energized during the periods in which direct current is applied at the exit end for the distant control of the wayside signals and until the entrance of a train into the track section shunts the track from transformer TB and deprives relay V of its alternating current.

An important feature of such an arrangement is of course the control of three indication wayside signals as well as the approach lighting of these wayside signals all without the use of control line circuits. It will also be apparent that the combination of coded direct current track circuit impulses separated by alternating current impulses for a cab signal control provides a feature wherein wayside signals can be supplemented by a cab signal system to obtain the well recognized advantages of such a combination with a minimum amount of additional apparatus.

The above rather specific description of one form of the present invention is given solely by the way of example, and is not intended, in any manner whatsoever, in a limiting sense. It is also to be understood that various modifications, alterations and adaptations may be applied to the particular form shown without departing from the spirit or scope of the present invention, except as limited by the appended claims.

What I claim is:—

1. In a railway signaling system, a plurality of track sections, means for applying spaced direct current impulses to the exit end of each section, means selecting the rate of said impulses in accordance with traffic conditions, a track relay at the entrance of each section operated by the direct current impulses, wayside signals at each section, means for controlling the wayside signals in accordance with the rate of operation of the associated track relay, a source of alternating current connected at the entrance end of each section, and an alternating current relay intermittently connected to the exit end of each section for controlling the energization of the associated wayside signal.

2. In a railway signaling system for wayside signals and for inductively controlling cab signals by alternating current impulses, a plurality of track sections, means for applying direct current impulses and alternating current impulses to the exit end of each section, means selecting the rate of said direct current impulses in accordance with traffic conditions, a track relay at the entrance end of each section operated by the direct current impulses, wayside signals at each section, means for controlling the wayside signals in accordance with the rate of operation of the associated track relay, an alternating current track circuit superimposed on each section, and means controlled by the alternating current track circuit for approach lighting the associated wayside signal the alternating current impulses separating the direct current impulses whereby to prevent such alternating current impulses from operating the approach lighting means.

3. In a railway signaling system, a plurality

of track sections, means for applying direct current impulses separated by alternating current impulses to the exit end of each section, means selecting the rate of said impulses in accordance with traffic conditions, car carried means controlled by the alternating current impulses, a track relay at the entrance of each section operated by the direct current impulses, wayside signals at each section, and means for controlling the wayside signals in accordance with the rate of operation of the associated track relay.

4. In a signaling system for railroads, a plurality of insulated track sections, wayside signals at each track section, a source of direct current and a source of alternating current at each section, means alternately connecting the source of direct current and the source of alternating current to the exit end of each track section, means selecting the rate at which the sources of direct and alternating current are alternately connected to the track sections in accordance with traffic conditions, car-carried signaling means controlled by the alternating current, a track relay at the entrance end of each section operated by the source of direct current, and wayside signal controlling means controlled by the operation and rate of operation of the associated track relay.

5. In a signaling system for railroads for wayside signals, and cab carried alternating current controlled signals, a plurality of insulated track sections, wayside signals at each track section, a source of direct current and a source of alternating current at each section, means alternately connecting the source of direct current and the source of alternating current to the exit end of each track section, means selecting the rate at which the source of direct current is alternately connected to the track sections in accordance with traffic conditions, car-carried signaling means governed in accordance with the presence or absence of such alternating current impulses, a track relay at the entrance end of each section operated by the source of direct current, wayside signal controlling means controlled by the operation and rate of operation of the associated track relay, an approach control relay responsive to alternating current only in series with the source of direct current at each section for controlling the energization of the associated wayside signals, and a source of alternating current connected to the entrance end of each section for normally energizing the associated approach control relay.

6. In a signaling system for railroads, a plurality of insulated track sections, wayside signals at each section, contact means at each section oscillating at either of two rates according to forward traffic conditions, a source of direct current connected to each track section through a front point of the associated contact means, a track relay at each section operated by the associated source of direct current, home signal control relays at each section controlled by the operation of the associated track relay, a distant signal control relay at each section controlled by the rate of operation of the associated track relay, and a source of alternating current selectively connected to the exit end of each track section through a back point of the associated contact means in accordance with forward traffic conditions whereby to condition car carried cab signals.

7. In a signaling system for railroads, a plurality of insulated track sections, wayside sig-

- nals at each section, contact means at each section oscillating at either of two rates according to forward traffic conditions, a source of direct current connected to each track section through a front point of the associated contact means, a track relay at each section operated by the associated source of direct current, home signal control relays at each section controlled by the operation of the associated track relay, a distant signal control relay at each section controlled by the rate of operation of the associated track relay, and a separate source of cab signal controlling current selectively connected to the exit end of each track section through a back point of the associated contact means.
8. In a railway signaling system having a plurality of track sections, a direct current track relay at the entrance end of each section, an oscillating contact means at the exit end of each section operable at different rates according to forward traffic conditions, a source of direct current connected to each track section through a front point of the associated oscillating contact means, wayside signal controlling means at each section controlled according to the rate of operation of the associated track relay, and a source of alternating current selectively connected to the exit end of each section through a back point of the associated oscillating contact means in accordance with traffic conditions whereby to inductively control cab signaling means.
9. In a railway signaling system, a plurality of insulated track sections, coding means operable to intermittently energize each track section with direct current impulses of distinctive code characteristics in accordance with traffic conditions, a direct current track relay at each section operated by the direct current impulses, decoding means associated with each track relay and responsive to the character of the code impulses energizing that relay, wayside signals controlled by the decoding means, means energizing each track section with alternating current impulses alternating with the direct current impulses, and signal means inductively controlled by the alternating current impulses.
10. In a railway signaling system, a plurality of track sections each including a direct current coded track circuit, an alternating current relay at one end of the track circuit in

series with the direct current track circuit, a source of alternating current at the other end of the track circuit intermittently energizing the alternating current relay, and wayside signals at the entrance to a given track section controlled by the direct current coded track circuit of that section and the alternating current relay of the next track section in the rear.

11. In a signaling system for railroads, a plurality of insulated track sections, wayside signals at each track section, a source of direct current and a source of alternating current at each section, means connecting the source of direct current and the source of alternating current to the exit end of each track section, means selecting the rate at which the sources of direct and alternating current are alternately connected to the track sections in accordance with traffic conditions, a track relay at the entrance end of each section operated by the source of direct current, car-carried cab signaling means controlled by the alternating current, and wayside signal controlling means controlled by the operation and rate of operation of the associated track relay.

12. In a signaling system for railroads, a plurality of insulated track sections, wayside signals at each track section, a source of direct current and a source of alternating current at each section, means connecting the source of direct current and the source of alternating current to the exit end of each track section, means selecting the rate at which the source of direct current is connected to the track sections in accordance with traffic conditions, cab signals controlled by the alternating current, a track relay at the entrance end of each section operated by the source of direct current, wayside signal controlling means controlled by the operation and rate of operation of the associated track relay, an approach control relay responsive to alternating current only in series with the source of direct current at each section for controlling the energization of the associated wayside signals, and a source of alternating current connected to the entrance end of each section for normally energizing the associated approach control relay.

WADE H. REICHARD.
